Patented Aug. 23, 1910.

UNITED STATES PATENT OFFICE.

WILLIAM REAGAN, OF PHILADELPHIA, PENNSYLVANIA.

ANTISKIDDING DEVICE.

968,416.

Specification of Letters Patent. Patented Aug. 23, 1910.

Application filed May 11, 1910. Serial No. 560,702.

To all whom it may concern:

Be it known that I, WILLIAM REAGAN, citizen of the United States, residing at Philadelphia, in the county of Philadelphia 5 and State of Pennsylvania, have invented certain new and useful Improvements in Antiskidding Devices; and I do hereby declare the following to be a full, clear, and exact description of the invention, such as 10 will enable others skilled in the art to which it appertains to make and use the same.

The invention relates to anti-skidding devices for vehicle-wheels, but more particularly for that class of wheels which are 15 provided with pneumatic or cushion tires; and it consists of groups of closely-related guard-members and calk-bearing members arranged, at intervals, around the circumference of the wheel.

20 One of the chief objects of the invention is to provide against abrading or cutting the tires.

Another object is to prevent the calks from penetrating the surface of the road-bed to such an extent as will tear up, or disfigure the same in case the surface is composed of asphaltum or concrete.

Other objects of the invention will become apparent upon a more complete disclosure 30 thereof.

In the drawings:—Figure 1 is a side elevation of an automobile wheel, showing my anti-skidding device applied thereto; Fig. 2, a transverse or cross-section of the tire, 35 showing a group of the anti-skidding members arranged thereon; Fig. 3, an outer face view of a similar group; Fig. 4, a perspective view of one of the guard-members and one of the calk-bearing sections pivoted together; Fig. 5, a vertical section of the interlocking device for securing the respective ends of the retaining-members together; Fig. 6, a side elevation of a group of modified guard-members, and calk-bearing members, and Fig. 7 a perspective view of one of the modified guard-members, with detachable back, showing a separate back applied thereto.

In the several views, the numeral 1 indicates a number of guard-members, preferably composed of two plates 2, 2, spaced apart and connected together at their back or under sides, as shown in Fig. 5. The backs of the guard-members are made 55 slightly rounding, especially their side

edges, so as to provide against all danger of abrading or cutting the tire, and to allow for a slight rolling motion on the tire. Pivoted between the guard-plates, at their adjacent ends, are calk-bearing members 3, 60 composed preferably of a plurality of plates provided with sharpened calks 4 for engaging the surface of the road-bed. The points of the calks are substantially in the same horizontal plane as the top edges of the 65 guard-plates forming the guard-members, and being thus protected the calks are prevented from entering the surface of the road-way to an extent sufficient to tear up or injure such surface, the top edges of said 70 guard-plates serving not only to limit the penetrating action of the calks, but to check the tendency to skid.

Pivoted to the end guard-member of each group of anti-skidding devices, is a securing-block 5 having oppositely-disposed hooks 6 which receive the slotted ends of links 7. The hooks of the securing-blocks are so constructed and arranged that, because of their pivotal relation with the said guard-members, disengagement of the links is prevented, 80 but withdrawal of the pintle will allow of the removal of the links from the hooks.

The respective ends of the retaining-members are securely fastened together by 85 an inter-locking device pivoted to one of the end links of said retaining-member, as shown at 8, Figs. 1 and 6. The interlocking device consists preferably of a suitable case 9, in one end of which is pivoted a locking-lever 10, having a hook-shape end 11 in which the slotted end of the other end link of the retaining-member is received, the case being provided with slotted-opening 12, 90 through which the end of the link is passed, when slipped over the locking-lever, into its seat in the hook-shape end. The pivotal point of the locking-lever is so located, with relation to the seat in the hook-shape end, that when the lever is pushed or forced into 95 locking position, the strain exerted by the retaining-member will firmly hold said lever against any accidental disengagement of the link.

Instead of employing the gripping devices 105 shown in Figs. 1 to 5 inclusive, I make the modified form shown in Figs. 6 and 7, in which the calk-bearing members are pivoted to guard-members not provided with back portions, being composed of guard-plates 13, 110

13, which have their back edges slightly curved, to conform to the lateral curvature of the tire, and their corners rounded, as have also the calk-bearing members 14, so 5 that the tendency to abrade or cut the tire is reduced to a minimum. This form of the device is especially adapted for use on cushion-tired wheels.

It will be noted that, while I have shown 10 the calk-bearing members composed of two plates or sections, they may be formed from a single plate of required width. It will also be noted that these members are of less width than the guard-members, and in consequence 15 thereof the tendency of the calks, which are thus protected by said guard-members, to tear up or mar the surface of the roadway, is further diminished, without affecting the gripping qualities of said calk-bearing sections, which, in practice, are shown to be highly efficient in preventing 20 skidding, but if desired a back 15, having bent-up sides 16 may be employed, so as to secure the results obtained by the guard-members 1, heretofore described.

Having thus fully described my invention, what I claim, is:—

1. An anti-skidding device for flexibly-tired wheels, including in combination calk-bearing-members, guard-members for limiting the penetration of the calks, said calk-bearing-members being pivoted between said guards, and detachably-connected securing-blocks at each end of the pivoted members.

35 2. An anti-skidding device for flexibly-tired wheels, including in combination calk-bearing-members, guard-members for limiting the penetration of the calks, said calk-bearing-members being pivoted between said 40 guards, and devices for retaining the pivoted members and guards onto the wheel.

3. An anti-skidding device for flexibly-tired wheels, including in combination calk-bearing-members and guard-members, said 45 calk-bearing-members being pivoted between said guards, the ends of the calks being in

substantially the same plane as the top edges of the guards.

4. An anti-skidding device for flexibly-tired wheels, including in combination calk-bearing-members, guard-members, said calk-bearing-members being pivoted between said guards, the ends of the calks being in substantially the same plane as the top edges of the guards, and retaining-links for holding 55 the pivoted members onto the wheel.

5. An anti-skidding device for flexibly-tired wheels, having in combination calk-bearing-members and guard-members pivoted together, the ends of the calks being 60 in substantially the same plane as the top edges of the guard-members, retaining-members composed of a plurality of links to which the pivoted members are connected, and interlocking means for fastening the 65 links together.

6. An anti-skidding device for flexibly-tired wheels, having in combination calk-bearing-members and guard-members pivoted together, the ends of the calks being 70 in substantially the same plane as the top edges of the guard-members, said guard-members being united by a back, slightly rounded, whereby abrasion and cutting of the tire is prevented.

7. An anti-skidding device for flexibly-tired wheels, comprising calk-bearing-members and guard-members pivoted together, said pivoted members being grouped at intervals around the wheel, the ends of the 80 calks being in substantially the same plane as the top edges of the guard-members, securing-blocks pivoted to each end of each group, retaining-links for holding the pivoted members onto the wheel, and means for 85 locking the end links together.

In testimony whereof I affix my signature, in the presence of two witnesses.

WILLIAM REAGAN.

Witnesses:

JAMES REAGAN,
J. W. CASSIDY.
